STATISTICAL MACHINE

William B. Austin, Ridgewood, N. J.

Application August 16, 1935, Serial No. 36,479

18 Claims. (Cl. 235—92)

This invention relates to improvements in statistical machines and has for a principal object the provision of an adding machine having electrically operated controls associated with the keys 5 of the adding machine for selecting for actuation one of a plurality of counters to be actuated by a power shaft in said machine.

Another object of the invention is the provision of an adding machine and a plurality of 10 counters, each of the latter being adapted to be mechanically driven synchronous with the operating cycle of the machine.

A further object of the invention is the provision of an adding machine having electrical contacts 15 associated with the keys, mechanically actuated counters adapted to be associated with the mechanism of the machine, and electrical devices connected in circuits with said contacts for associating the counters with said mechanism.

Still another object of the invention is the provision of a machine having accumulating and printing mechanisms, keys for effecting set ups in said mechanisms and a plurality of counting 20 devices operable in synchronism with said mechanisms, and electrically operated instrumentalities for associating a device with the mechanism, one of said devices being provided for each combination of one or more of said keys.

A further object of the invention is the provision 25 of key mechanism for listing and totalizing numerical data or the like, the provision of other mechanism, actuated by said first mechanism, for counting, one of said devices being provided for each possible combination of keys, and electrical- 30 ly controlled means selecting said devices, whereby a statistical count is obtained as a by-product of the listings entered into said mechanism.

Other objects and advantages of this invention 35 will be obvious to those skilled in the art.

In certain types of statistical work it is desired to obtain a count of the number of times any given figure may appear in a large number of items. As an example of this, a case 40 might be taken where a light and power company wishes to make a rate study to determine how many consumers have used, for example, 10 kilowatt hours in a month, how many 11 kilowatt hours, how many 12 kilowatt hours, etc., 45 possibly from 0 kilowatt hours up to 1,000 kilowatt hours. By existing methods and devices such a rate study requires a great many steps and is an expensive procedure.

By means of the device, which is the subject 50 of the present application, rate studies may

be obtained as a by-product of other work which has to be done. For example, the bills must be added up to determine what total the bills for a month amount to and a rate study may be obtained as a by-product of this operation without involving any more time than is required to enter the items into the adding machine and totalize them.

Another example of the use of the present invention is in questionnaire work. The answers 10 to questions may be numbered with a code number and thereby the device can be caused to count how many people give answer No. 20, answer No. 506, answer No. 999, etc.

In using the device herein shown and de- 15 scribed, a plurality of counters is associated with this adding machine, one counter for each number, figure or amount from 0 to 999. It is obvious that the number of counters may be increased or decreased in accordance with the usage to which 20 the machine is to be put. The counters are not disturbed during the entire operation of totalizing the bills; for example; and after the operation has been completed the total counts of all 25 of the counters is printed on a collective sheet, preferably in one operation.

Of course, it is obvious that as many printings as desired may be taken from these counters from time to time as the work progresses but it is usual to take the final totals of counts entered 30 into these counters at the end of an operation.

Referring to the drawings:

Figures 21a, 21b and 21c, together, constitute a circuit diagram of the electrical controls of the device; and

Figure 22 is a perspective view of a part of the mechanism shown in the lower right hand portion of Figure 11 for preventing the machine from becoming wrecked or damaged in the case of a jam.

This application is a continuation in part of application Serial No. 24,332, filed May 31, 1935.

While any type of adding machine may be used in connection with the relays, circuits, and counters provided the keys are provided with contacts, in the embodiment shown applicant has selected an adding machine of the "Burroughs" type, such as shown and described in Patent No. 1,914,401 issued June 20, 1933, to T. M. Butler.

The counters in the present application are similar to those shown in Figures 5 and 6 of the copending application with the exception that instead of being electrically actuated, the counters in the present application are mechanically actuated, and electrically selected for actuation. Referring to Figures 4 to 8, the counter, generally designated by the numeral 25, is comprised of a shaft 26 suitably journaled in a supporting plate. The shaft 26 carries a plurality of counter wheels 28, each of which is provided with an internal pawl 29 which is engaged by a keyway 30 when the counters are reset. This will presently be described.

Each counter wheel has secured, on one side thereof, a ten toothed ratchet 31 having curved recesses 32 between each of nine of the teeth and a deeper recess 33 between the 1st and 10th tooth for the purpose of "carry-over", as de-

scribed in the copending application above referred to. These curved recesses are successively engaged by a lever member 34 to prevent the counter wheel from "over-running".

A spring 35 is provided for retaining the member 34 in engagement with the ratchet wheel 31, one end of the spring being secured to the member and the other end to a metallic block 36 which also forms a support for the member 34.

The members 34 are positioned and spaced apart by suitable slots in the block 36, and a pin 37 serves as a pivotal support for the members 34.

The block 36 has a cut away portion 38 forming a recess therein. A yoke 39 is pivotally mounted in this depression by means of a pivot pin 40. The yoke 39 has pivoted thereto a pawl member 41 carrying at its upper end a plurality of pawls 42, 43, 44, 45 and 46 of different lengths. A spring 47 is provided to retain one or more of the pawls in engagement with one or more of the ratchets 31.

A pair of offset arms 48 and 49 are secured together and pivoted in the yoke 39 by means of a pivot pin 50. These arms are secured together at their other end by means of a pin 51 passing through a slot 52 formed in the bar 53. The pin 51 also passes through a slot 54 formed in the links 55. A spring 56, extending from a midpoint of the pin 50 to a point 57, supported in the metallic block, serves to bring the yoke 39 and the pawl member 41 back to a normal position after the latter has been actuated.

Suitable bearings 58 and 59 are provided on the plate 27 to permit the bar 53 to be reciprocated. The bar 53 is provided with a stop pin 60 to limit its motion in one direction and a stop pin 61 to limit its motion in the other direction.

A spring 62 engages a hole 63 in one end of the bar 53 and has its other end secured to a stud 64 mounted on the plate 27, serving to urge the bar 53 to the right, as viewed in Figures 5 to 9 inclusive, with the stop pin 61 in engagement with the outside of the bearing 59.

A shaft 65 is journaled in the plate 27, preferably parallel to the shaft 26, and a second shaft 66 is also journaled in the plate 27 adjacent to and parallel to the shaft 65.

A dog 67 is carried by the shaft 65 and is rotated through various portions of a revolution, the position of the slot 54 in the links 55 being varied relative to the slot 52 in the bar 53.

The shaft 66 has secured thereto a lever 69, and the bar 53 carries a stud 70 which is engaged by the lever 69 when the shaft 66 is rotated.

With the shaft 65 in the position shown in Figure 5 the slot 54 in the link 55 is almost parallel to the slot 52 in the bar 53. When the shaft 66 is rotated in a counter-clockwise direction the lever 69 engages the stud 70 and moves the bar 53 to the left to the position shown in Figure 6.

The movement of the bar 53 brings the slots 52 and 54 into alignment, the pin 51 floats freely therein and the pawl member 41 is not actuated, therefore the counter wheels do not move.

When the shaft 65 is rotated to the position shown in Figure 7 the slot 54 is in crosswise relation to the slot 52 so that when the bar 53 is moved to the left the pin 51 is, due to the combined action of the slots 52 and 54, moved in an upward direction to the position shown in Figure 8. In this latter position the pawl member 41, through the movement of the arms 48 and 49, is moved upward to advance the counter a value of "one".

By referring to Figure 9, in which a group of 75

counters is shown, it will be noted that the shaft 65 associated with the first counter and the shaft 65a associated with the second counter, are in the position shown in Figure 5, and that the shaft 65b, associated with the third counter, is in the position shown in Figure 7; accordingly, the slot 54b in Figure 9 is almost at a right angle to the slot 52b and, therefore, when the bar 53 is moved to the left, a counter wheel in the third counter, designated by the numeral 28b, will be actuated and the counter wheels in the first and second counters, designated by the numerals 28 and 28a respectively, will not be affected, although all three of these counters are banked together.

Figures 5 to 9, inclusive, have been included in this application in order that the simple manner of controlling the actuation of the counters can be explained.

20 In the preferred embodiment of the invention, the effect of partly rotating the shaft 65 is accomplished by a mechanical member electrically selected. Likewise, the action of the shaft 66 and the lever 69 is electrically associated with the 25 movement of an oscillating shaft in the adding machine per se.

Referring to Figures 11 and 12:

The bar 71 is oscillated by an oscillating shaft in the adding machine through suitable linkage 30 which will presently be described. In Figure 11, the counters are identical with those shown in Figures 5 to 9 inclusive. The counter wheel in one of these counters in Figure 11 is designated by 28c, the counter wheel in another by 28d and 35 the counter wheel in a third by 28e. The other parts of the counters are designated by the same numerals given in Figures 5 to 8 with the exception that the three counters and parts thereof have the additional designation of c, d, or e.

40 The bar 71 is provided with suitable guide blocks 72 which are supported on the end plate 74 in such manner that the bar may freely reciprocate thereon. A pivot pin 75 extends through the bar 71 to a point outside the plate 74. A 45 pair of link members 76 and 77 engage the pin 75, one on each side of the bar, and are retained on the pin by suitable cotter pins 78. A lever 79 is pivotally secured to the links 76 and 77 by means of a pivot pin 80. Suitable cotter pins, 50 one of which is shown at 81, pass through the pin 80 at either end thereof to secure the links and the lever 79 in pivotal relation.

A block 82 preferably formed of metal, is supported on a sub-frame 83 and has mounted thereon in a pivot pin 84. The lower end of the lever 79 is pivoted on the pin 84 and secured in proper relation theron by means of cotter pins. The lever 79 has pivoted thereto, between the ends thereof, an elongated rectangular member 85, 60 said member being pivotally secured to the lever by means of a pivot pin 86, preferably positioned near one end of the member 85.

The member 85 has a longitudinal hole 87 formed therein and extending from a point near one end of the member to a point near the other end of the member. A slot 88 is formed in the member 85 communicating with the hole 87. A spring 89 and a hardened metallic block 90 are positioned in the hole 87 with the block 90 in 65 the vicinity of the mid-portion of the length of the hole. A similar hardened metallic block 91 and a spring 92 are positioned in the hole 87 and oppositely disposed to the first block and spring. The function of these blocks will presently be described.

Referring to Figure 2, the adding machine has a shaft, indicated by the numeral 93, which oscillates each time the adding machine is operated. The end of the shaft 93 opposite to the end viewed in Figure 2, projects from the adding machine and has an extension shaft 94 secured thereto in driving relation as viewed in Figure 14.

5 A shaft 95 is positioned, preferably at right angles to the shaft 94, in a horizontal plane. A bevelled gear 96 is secured to the shaft 94 in any suitable manner: for example by means of a taper pin 97, and meshes with a bevelled gear 98 which is secured in driving relation to the shaft 95 so that for each operating cycle of the adding machine the shaft 94 together with the shaft 95 10 oscillates in timed relation to a definite portion of said cycle.

A dog 99 is mounted on the shaft 95 in driving relation thereto. The dog 99 has a stud shaft 100 extending therefrom. This shaft projects 20 into the slot 88 formed in the member 85 and is engaged on one side by the block 90 and on the other side by the block 91.

25 As the springs 89 and 92 respectively exert an equal pressure against the stud shaft 100, motion will be transmitted to the lever 79 through the medium of the member 85 and the pivot pin 86, each time the shaft 95 is oscillated provided none of the mechanism associated with the lever 79 becomes locked.

30 In case any of the mechanism does jam the machine will not become wrecked due to the fact that either the spring 89 or the spring 92 is resilient, and the slot is of such length that the stud shaft can move the length of its stroke 35 therein.

In the embodiment shown in Figure 11 the bar 53 is positioned on the opposite side of the plate 74 to that of the bar 71. The bar 53 is supported on suitable bearings 58 and is provided with slots 52, one for each counter.

The arrangement of the offset arms 48 and 49, the pin 51, the slot 52, the slot 54 and the link 55 is exactly as shown in Figures 5 to 8, inclusive. The shafts 65c and 66c are provided for controlling entries into the extreme left hand or c counter in Figure 11; the shafts 65d and 66d are associated with the second or d counter; and the shafts 65e and 66e are associated with the third or e counter. The shafts 65c, 65d and 65e are respectively provided with dogs 67c, 67d and 67e. These shafts are preferably square, thereby avoiding the necessity of providing keyways therein. The outer end of each of these shafts has a hole formed therein to 55 accommodate a spring 102. Figure 12. Each shaft is provided with an engaging member generally designated by the numeral 103. The engaging member 103 consists of a hollow and dome shaped cup 104, having a square hole 105 formed 60 therein. The cup 104 has secured thereto an arm 106 having a slot 107 formed therein at the upper end thereof as viewed in Figure 11. The arm 106 has a tail 108 extending therefrom and projecting below the cup 104 as viewed in Figure 11. The bar 71 is provided with a plurality of studs 109 which project therefrom in the manner shown in Figure 12. The springs 102 acting against the inside of the cups, normally hold the arms 106 out of engagement with the studs 109. 65 The operation of the engaging members 103 will presently be described.

An electromagnet 110 is mounted on a suitable supporting plate 111 and a similar magnet 112 is mounted on a supporting plate 113. In 70 75

order to conserve space in the device the magnet 112 is preferably mounted in an inverted position. A pair of these magnets (one upright magnet 110 and one inverted magnet 112) is provided for controlling the selection of each counter. The plates 111 and 113 are spaced apart by means of a rectangular tube 114. The magnet 110 is provided with an armature 115 pivoted by means of a pivot pin 116 and having an arm 117 extending through a hole 118 formed in the plate 111, to engage the domed end of the cup 104.

The armature 115 also has secured thereto, by rivets or any other suitable means, a piece of insulation 119. A helical length of wire 120 and a second helical length of wire 121 are disposed substantially parallel to each other and preferably in light contact with the insulating block 119. A stationary block of insulation 122 is positioned near the helical wires 120 and 121 and a metallic member 123 is secured to the block 122 in such position that when the armature 115 is in its normal position, as shown in Figure 12, the helical wires 120 and 121 do not make contact therewith.

25 The magnet 112 has its armature (not shown) arranged in a like manner and provided with an insulating strip and helical wires in the same manner described for the magnet 110. An arm, associated with the armature 115 of the magnet 30 112, designated by the numeral 124, engages the domed end of a similar cup.

The arm 124, associated with the magnet 112, would act against the domed end of an engaging member associated with the shaft 65e, for example, and the arm 117 actuated by the magnet 110 would control the movement of an engaging member carried by the shaft 66e, for example (it being understood that all of the square shafts 65c, 65d and 65e, and 66c, 66d and 66e, are provided with engaging members 103).

40 The armature and arms associated with any of the magnets 110 and 112 perform two functions:

(a) They shift the engaging members 103 into engagement with the studs 109, and at the same time,

(b) They press the helical wires 120 and 121 into engagement with the metallic member 123.

50 The wires 120 and 121 are included in circuits which will presently be described in connection with the circuit diagram of the machine.

In addition to the counters, above described, having counter wheels 28, the device may be provided with a plurality of other counters, generally designated by the numeral 125, and shown in Figures 10 and 11. These counters have counter wheels 128 which are identical to the counter wheel 28 and are mounted on the shaft 126 suitably journaled in the plate 127. The shaft 126 is provided with a keyway in the same manner as the shaft 30 and a pawl 129 engages the keyway 130 in the same manner that the pawl 29 engages the keyway 30. The other parts of the counters 125 are identical with the parts of the first counters described, and like parts of the new counters bear numerals which run 100 higher than the numerals on the parts of the first counters, through the numeral 147.

Instead of the offset arms 48 and 49, the counters 125 are provided with a stud 148. A bar 149 is mounted on suitable supports, not shown, for reciprocation beneath the counters 125 and adjacent to the end of the stud 148. The means for reciprocating the bar 149 will presently be 75 described.

The bar 149 is provided with a member 151 carried on a suitable pivot 152 supported on the bar 149. The member 151 is provided with a notch 153, a camming surface 154 and a camming lobe 155. The member 151 is also provided with a toothed portion 156, and may be retained in one or the other of two extreme positions by means of a toggle spring 157 carried by the bar 149. The member 151 is shown in solid lines in Figure 10 and it will only actuate its associated counter when positioned as shown in dotted lines. The normal position is that shown in solid lines.

The shaft 95 has secured thereto a dog 158 which is in turn connected to an arm 159 by means of a link 160 and pins 161, 162. The arm 159 has one end thereof pivoted to a bracket 163 by means of a pivot pin 164 passing therethrough. The bracket 163 may be secured in any suitable manner to a support 165 in the machine. A curved link 166 has one end thereof pivoted to the pivot pin 152 and its other end pivoted to the upper end of the arm 159 by means of a pivot pin 167.

Due to this arrangement each time the shaft 95 is oscillated by the adding machine mechanism, as above described, the bar 149 is reciprocated on its supports and the member 151, carried thereby, is moved relative to the camming stud 148, but when the member 151 is in its normal position, as shown in solid lines in Figure 10, the camming stud 148 is not engaged.

A magnet 168, supported on the frame 74 by a suitable bracket 169, is provided for actuating the member 151. This magnet is provided with a core 170 carrying a suitable winding and mounted in a shell 171 which forms a return path for the magnetic flux. An armature 172 is pivoted to the shell 171 by means of a pivot pin 173 and an arm secured to the armature 172 is of such proportions that when the armature 172 is in its normal position the member 151 carried by the bar 149 may be retained in its normal position by the toggle spring 157.

When the magnet 168 is energized, the armature 172 is attracted and the motion imparted by the arm 174 is in turn passed on to the member 151 causing the latter to assume the position shown in dotted lines in Figure 10.

When the member 151 has been actuated and is in the position shown in the dotted lines in Figure 10, the surface 153a of the notch 153 engages the end of the camming stud 148 and, as the bar 149 is moved to the right, as viewed in Figure 10, the yoke 139 is caused to swing upwardly on its pivot pin 140 and one or more of the pawls 142 to 146 will engage a depression 132 or 133 in the counter wheel 128 and cause the same to add the value of 1.

On the return stroke, in which the bar 149 moves to the left, either the action of the camming surface 154 or the camming lobe 155 against the camming stud 148 will cause the member 151 to be thrown down to the normal position, shown in solid lines, and so retained by the toggle spring until the magnet 168 is again energized.

The device is also provided with a plurality of relays 175 having contacts which are closed electrically and which are opened or reset mechanically. One of these relays, (shown diagrammatically in Figure 17) is provided with a magnet 70 coil 176, an armature 177 and an arm 178. The arm 178 is provided with a stud of insulation 179 which, when the armature 177 is actuated, engages a contact arm 180 carrying a contact point 181 and moves the latter into engagement with 75

a contact point 182 carried by a contact arm 183.

An arm 184, supported on a pivot pin 185, is adapted to lock the arm 178, the stud of insulation 179 and the contact points 181 and 182 into engagement when the armature 177 is attracted by the magnet 176.

A suitable counterweight 186 is connected to the arm 184 on the opposite side of the pivot pin 185 to facilitate this action.

- 10 The shaft 95 has a disc 187 keyed thereto. A pin 188 is mounted in the disc. A bracket 189 is secured to the supporting member 165 and has a pin 190 projecting therefrom in line with the pin 188. A lever 191 is provided with a V-shaped hook which is engaged by the pin 188 during a portion of the oscillating movement of the shaft 95. The end of the lever adjacent to the hook is provided with a camming surface 193, which, acting against the pin 190, when the shaft 95 and disc 187 are moving in a clockwise direction, as viewed in Figure 17, causes the hook 192 to become disengaged from the pin 188. The timing of this disengagement may be set within certain limits according to the positions of the pins 188 and 190.

20 The lever 191 is pivoted to a bar 194 by means of a pivot pin 195, and an ear 196, formed integral with the lever 191, has one end of a spring 197 secured thereto for holding the hook 192 and the camming surface 193 in contact with the pins 188 and 190. The other end of the spring 197 is secured to a stud 198 carried by the bar 194. This bar is supported in suitable bearings, one of which is shown at 199, in which it may reciprocate.

30 One end of a link 200 is connected to the bar 194, at one end thereof, by means of a pivot pin 201. The other end of the link 200 is connected to a lever 203 by means of a pivot pin 202. The lever 203 is maintained in fixed relation to a lever 204 and pivoted on a pivot shaft 205.

40 The lever 204 has an angular portion 206 which rides a bar 207, and a pin 208 in this bar is normally maintained in contact with the angular portion 206, for example, by means of a spring, not shown.

50 A lever 209 consists of a straight portion 210, a portion 211 angular with respect to the portion 210, and a portion 212 which is preferably spaced apart from and parallel to the portion 210. This lever is pivoted on a pivot shaft 213 and is connected to the bar 207 by means of a pivot pin 214.

55 When the magnet coil 176 is energized the armature 177 is attracted thereby, the arm 178 through the medium of the stud 179, closes the contacts 181 and 182, and the lever 184 engages and latches the arm 178 to hold the contact points in closed relation, which is shown in Figure 17. This occurs during the forward oscillation of the shaft 95.

60 During the backward oscillation of the shaft 95, which is clockwise as viewed in Figure 17, the pin 188 is in engagement with the V-shaped hook and the pin 190 is in engagement with the surface 193. As the disc 187 moves in a clockwise direction the pin 188 causes the bar 194 to move to the left in its bearings 199. This movement is imparted to the levers 203 and 204 through the medium of the link 200 causing the lever 204 to swing upward in a counterclockwise direction and the camming action of the angular portion 206 against the pin 208 causes the bar 207 to move to the right as viewed in Figure 17, thereby swinging the lever 209 in a clockwise direction about the pivot shaft 213 whereupon the

portion 212 raises the counterweight 186 and causes the arm 184 to move downwardly and release the arm 178. The mechanism is so timed and synchronized that by the time the arm 184 is moved downwardly to release the arm 178, the keys have been reset, the key contacts have been opened, and the magnets 110, 112, have been deenergized, thereby releasing the arms 119 and disassociating the conductors 120, 121, from the strip 123. The description of these elements and the circuits associated therewith will be herein-after described.

10 The release of the arm 178 permits the contact points 181, 182 to open and the relay is reset in readiness for another operation. A plurality of 15 multi-contact relays, designated generally by the numeral 215, each have magnet coils 216, and an armature 217 in cooperative relation therewith (Figure 18).

20 The armature has secured thereto an insulating block 218 carrying a contact pin 219 on the upper side thereof, as viewed in Figure 18, and a metallic contact strip 220 on the lower face thereof. The contact point 219 and the contact strip 220 are connected together and to 25 a flexible lead 221 (the insulation 218 insulating these contacts from the armature 217). The relays are each provided with a contact arm carrying a contact point 223. Normally 30 the armature 217 is in such a position that the contact points 219 and 223 are in engagement.

35 An insulating block 224 is positioned beneath the metallic strip 220 and carries a plurality of plungers, one of which is designated by the 35 numeral 225, which is so proportioned that when the armature 217 is actuated by the magnet 216 all of the plungers 225 are connected in common by means of the metallic strip 220.

40 In order to take care of any inequalities in the surface of the strip 220 and also in order to effect a slight wiping contact between the plungers 225 and the strip 220, the plungers are each provided with a spring 226 for urging the plungers upwardly as viewed in Figure 18. Each plunger is provided with a shoulder 227 for limiting its extreme upward movement. The lower end of the spring bottoms against a metallic member 228 in the block 224, and each metallic member extends downwardly from the block 224 to facilitate making electrical connections thereto.

50 In the embodiment of the relays shown in the present application, it has been found preferable to employ ten plungers 225 to each relay. The arrangement of these plungers relative to each other is shown in Figure 19.

55 Referring to Figures 14, 15 and 16, the device is provided with an "on" key 229 for operatively associating the mechanism with the adding machine mechanism, and an "off" key 230 for disassociating the mechanism from the adding machine mechanism. The hub 231 of the bevelled gear 98 is faced off and is provided with a hole 232 parallel to the shaft 95 and forms the stationary half of a clutch.

60 The shaft 95 is provided with a long key 233. A collar 234 forms a working fit on the shaft 95 and is provided with a keyway (not shown) which rides on the key 233. The collar has a groove 235 formed therein, and the face of the collar adjacent to the hub 231 is provided with a pin 236 70 extending therefrom in parallel to the shaft 95, which, when the clutch is engaged, fits into the hole 232 and transmits motion from the gear 98 to the shaft 95.

75 The "on" key 229 is secured to a shaft 237 75

which is supported in suitable bearings 238, which is in turn supported by a bracket 239 secured to the base or supporting member 165.

The shaft 237 has secured thereto an arm 240 and an arm 241 which together might constitute a fork, one of these arms being positioned on each side of the collar 234. The arm 240 is provided with a pin 242 which engages the groove 235 on one side of the collar and the arm 241 is provided 10 with a pin 243 which engages the groove 235 at a point opposite the pin 242, so that when the "on" key 229 is depressed, the collar 234 is moved into engagement with the hub 231 and with the pin 236 positioned in the hole 232 thereby placing 15 the shaft 95 in driven relation to the gear 98. The shaft 237 also has secured thereto a collar 244 having a stud 245 projecting therefrom. The stud 245 extends between a pair of contact arms 246-247 and a second pair of contact arms 20 248-249. When the "on" key 229 is depressed, the shaft 237, as viewed in Figure 15, is moved in a counterclockwise direction and the contact arms 248-249, which are normally in contact 25 with each other, are opened, and the contact arms 246, 247, which are normally open, are brought into contact with each other.

The function of these contact arms will presently be described in connection with the circuit diagram of the device.

30 The shaft 237 is also provided with an arm 250 and has a notch 251 formed near the outer end thereof, as viewed in Figure 16 and in line with the "off" key 250 in Figure 14. This notch is made in the form of a V and is engaged by the 35 upper end of the lever 252. A lever 252 pivoted on a pin 253 is mounted preferably in a vertical plane and normally, when the key 229 has not been depressed, rests against the end of the arm 250 engaging the notch 251. A spring 254, having 40 one end secured to the lever 252 and the other end secured to a stud 255, suitably supported on the frame, urges the lever 252 against the end of the arm 250.

When the "on" key 229 is depressed, the lever 45 250 is moved upwardly as viewed in Figure 16 and the upper end of the lever 252 engages the notch 251 and retains the key 229 in its depressed position, at the same time retaining the clutch members 231 and 234 in engagement.

50 The "off" key 230 is pivotally mounted on the shaft 237 and has extending therefrom an arm 256 carrying a camming member 257. The camming member is of such form and so positioned that when the "off" key 230 is depressed, the lever 55 252, which is engaged by the camming member 257, by this action, is disengaged from the notch 251 and moved to the right as viewed in Figure 16, thereby permitting the clutch members 231, 234 to become disengaged and, in effect, disconnecting the shaft 95 from the shaft 94 which is driven by the adding machine.

At the same time, due to the presence of the pin 245 between the contact arms, the contact arms 246, 247 are opened and 248, 249 are closed.

65 A pair of contact arms 258, 259 is mounted on the lever 79, Figure 11; a pin 260, Figure 11, Figure 15, and Figure 22, is carried by a Bakelite link 261 and extends between these contact arms. This link has a hole formed therein at one end 70 thereof fitting the stud shaft 100. The other end of the Bakelite link 261 is reciprocably supported on the member 85, adjacent to the end of the latter, which is secured to the lever 79, a slot 262, formed in the member 85, being provided for this 75 purpose.

In case of any jamming of the mechanism associated with the bars 53 or 71, as above described, the spring 89 or the spring 92 will compress, due to the movement of the stud shaft 100 and the lever 79 will not be actuated when this occurs, the movement of the stud 100 is imparted to the pin 260 through the medium of the Bakelite link 261, and thereby the contact arms 258 and 259 are separated to open the circuit, as will presently be described.

When the machine operates normally the lever 79 moves with the stud shaft 100 and since the contact arms 258, 259 are mounted on and moved with the lever 79 these contact arms are not opened. In other words, they remain normally closed until such time as the mechanism might become jammed, whereupon they open and disable the circuits in the machine.

In the present embodiment of the invention, the "units", "tens" and "hundreds" keys, in the 20 adding machine, are each provided with a pair of contacts which are normally open and which are closed when the key associated therewith is depressed.

One row of these contacts is shown in Figures 2 and 21c and designated by the numerals 263 and 264. Each key of the adding machine in the "units", "tens" and "hundreds" row, in addition to controlling the movement of a differential stop bar 265, also closes a pair of contacts 263, 264 25 associated therewith, and maintains them in this relation until the reset cycle in the adding machine occurs. The key is maintained in the depressed position by means of the action of a slideable control member 266 in the usual manner. Each slideable control member 266 is provided with a curved end 267 which engages an upstanding projection 268 formed integral with a yoke 269. As these machines are well known in the art their functions will not be described in so far 40 as the adding machine per se is concerned.

A rocking member 270 includes a forked portion engaging a shaft 271 and has secured thereto a contact actuating member 272 which presses against a movable contact member 273 and shifts 45 the position of the latter each time the member 270 is rocked. Referring to Figure 3, the contact member and its associated contact arms are shown enlarged for clarity.

The movable contact member 273 consists of 50 a contact arm 274, a second movable contact arm 275 tied together with a bar of insulation 276. A spring 277 has one end thereof secured to the bar 276 and the other end is secured to a stationary member in the adding machine, designated by the 55 numeral 278, at the point 279. The point 279 is so positioned that when the bar, together with the arms 274 and 275, are on one side of the center line, the arm 275 is maintained in contact with a stationary contact arm 280, and the contact 60 arm 274 is maintained in contact with a stationary contact arm 281.

The end of the actuating member 272 acts against the bar 276 and swings the contact arms 274 and 275 in a clockwise direction, as viewed 65 in Figure 3. When dead center is passed the spring 277 propels the contact arm 275 into contact relation with a stationary contact arm 282 and the contact arm 274 into contact relation with a stationary contact arm 283. These contact arms and contact members maintain a "zero" 70 circuit, which will presently be described in connection with the circuit diagram.

As will be pointed out presently in connection with the circuit diagram, some of the differential 75

stop bars have two, instead of three, contact arms associated therewith.

- 5 Periodically, during a rate study, and when the rate study is completed, it may be desired to print the results shown in the counters. A simple means is provided for this purpose, a portion of which is shown diagrammatically in Figure 20. The counter wheels are designated by the numerals 28, a sheet of paper by the numeral 284, 10 and a sheet of carbon or ribbon by the numeral 285. A stationary member 286 may be secured to the device in any suitable manner and a bar 287 is arranged to reciprocate thereon. The bar is provided with a plurality of slots 288 each having an associated pin 289 secured to the stationary member 286. The bar 287 also carries a plurality of shafts 290, 290a, one for each row of counter wheels 28. Each shaft 290 carries a platen roller 291.
- 15 20 A contact arm 292 and a cooperating contact arm 293 are insulatedly supported on the stationary member 286. The contact arm 292 is so mounted, relative to the contact arm 293, that it tends to open the contact points 294 and 295.
- 25 The contact arm 292 carries a camming member 296 which is engaged by the platen roller 291 when the bar 287 is in its extreme upper position, as viewed in Figure 20, thereby maintaining the contact points 294 and 295 in contact with each other.

30 When it is desired to print, the bar 287 is moved downwardly. During the first portion of its movement downwardly, due to the sliding portion of the slots, the platen rollers are moved over to the left in the vicinity of the counter wheels 28.

35 Further movement of the bar 287 downwardly is straight and parallel to the counter wheels due to the straight portion of the slots 288, causing the platen rollers 291, 291a to pass over the surfaces of the counter wheels 28 and thereby impressing on the sheet of paper visible characters which constitute a record of the values entered into the counter wheels.

40 45 Due to the downward movement of the bar 287 the platen roller 291 is disengaged from the camming member 296 thereby permitting the contacts 294 and 295 to become separated and disabling the electrical circuits in the device as will later be pointed out.

50 Each counter is provided with a gear or pinion 452 keyed to its shaft. Racks (not shown) mesh with these pinions and are provided so that the counter shafts 26 and 126 may be rotated forward to reset the counter wheels. When the shafts are rotated forward the keyways 30 and 130 engage the pawls 129 within the counter wheels and thereby the counter wheels are reset to "0".

55 60 For the convenience of the operator, the device is built into a table or desk 297 having a depressed portion 298 formed therein to support the adding machine 299. The top of the desk is provided with doors 300, 301 and 302. The shaft 65 94 extends from the right side of the adding machine into the compartment below the door 300 and a portion of the shaft 95 is also accessible through the door 300.

70 The counters and the printing mechanism are accessible through the door 302 while the relays and other control devices are accessible through the door 301.

75 Referring to Figures 21a, 21b and 21c, which, together constitute a circuit diagram of the device, it will be noted that the contact points 263

associated with the row 303 of "units" keys are individually connected via the cable 304 to a corresponding lower magnet 112 in each of the banks of magnets 305, 306 and 307. For example, clarifying this, the contact 263 associated with the "1" key in the "units" row is connected to the 1 magnet in the bank 305, to the 1 magnet in the bank 306, to the 1 magnet in the bank 307, etc.

80 The portion of the "zero" circuit associated with the "units" keys, which is normally effective when none of the "units" keys, 1 to 9, have been operated, has the contact arm 290 connected via the same cable 304 to one side of the 0 magnet in the bank 305, and to one side of the 0 magnet in the bank 306. The contact arms 264, which cooperate with the contact arms 263, are connected in common by means of a wire 308, which in turn is connected to other wires which will presently be described.

85 The contact arms 263a associated with the row 309 of "tens" keys are each connected via a cable 310 to one side of corresponding upper magnet coils 110 in the banks 311, 312 and 313. For example, the contact arm 263a, associated with the "5" key in the "tens" row is connected to one side of the "5" magnet in each of the groups 311, 312 and 313.

90 The contact arm 280a, which forms a part of the "zero" circuit, normally closed when none of the "tens" keys in the row 309 have been depressed, is connected via the cable 310 to one side of the 0 magnet in each of the banks 311, 312 and 313.

95 The contact arms 264a in the "tens" row, which cooperate with the contact arms 263a, are all connected in common by means of a wire 314. The other sides of all of these magnets are connected as follows:

100 The return wires of the magnets in the bank 311 are each connected by a cable 315 to a group of plunger contacts 225 in the block 224. The contact strip 220 is connected by means of a wire 316 to the contact arm 222d. The contact arm 222, which is normally in contact with the contact strip 220, is connected by means of a wire 317, to the contact strip 220b.

105 The return wires of the magnets in the bank 305 are connected by means of a cable 318 to the plunger contacts 225a in block 224a. The contact strip 220a is connected by means of a wire 319 to the contact arm 222e. The contact strip 220e cooperating therewith, is connected by means of a wire 320 to a resistor 321. This resistor is connected through a series of circuits, 110 which in turn connect to the positive side of the line. This series of circuits may be traced as follows:

115 From the "units" resistor 321 to a bus wire 322, via a wire 323, the contact arm 293, thence via the contact points 294 and 295 to the contact arm 292. From the contact arm 292 current is led by a wire 324 by the contact arm 258, thence to the contact arm 259 and via the wire 325 to the contact arm 246. When the "on" key 229 is depressed the contact arms 246 and 247 are in contact further current will flow from 246 to the contact arm 247 and via the wire 326 to one of the center contacts 328 of the double pole, double throw switch 327, from which it passes via the plate 329 to the switch contact 330 and via the wire 331 to the contact 332 of the double pole, double throw switch 333, thence via the plate 334 to the center contact 335, and via the wire 336 to the positive side of the line.

As described above, it is preferable that the circuits to the counter magnets be disabled during a printing operation. Accordingly, this circuit will be interrupted by the opening of the contact arms 292, 293 during a printing operation.

It is also described above that the circuits should be disabled in case the mechanism becomes "hung up". This is effected by separating the contact arms 258 and 259. It was also pointed out above, in connection with Figures 14, 15 and 16, that when the "off" key 230 was depressed, the contacts 246 and 247 are interrupted. As these contacts are included in this circuit it is obvious that the opening of these contacts will disable these circuits.

The return wires of the magnets in the bank 312 are connected via a cable 337 to the plunger contacts 225d. The contact strip 220d is connected via a wire 338 to the "tens" resistor 339 which is in turn, connected to the bus wire 322.

The return wires of the magnets in the bank 306 are connected via a cable 340 to the plunger contacts 225e.

The return wires of the magnets in the bank 313 are connected via a cable 341 to the plunger contacts 225b. The return wires of the magnets in the bank 307 are connected by a cable 342 to the plunger contacts 225c. The contact strip 220c is connected via a wire 343 to the contact arm 222a.

A magnet coil 216 is provided for actuating the contact strip 220; and a magnet coil 216a is provided for actuating the contact strip 220a. Likewise, a magnet coil 216b is associated with the strip 220b; and a magnet coil 216c is associated with the strip 220c; a magnet coil 216d is associated with the strip 220d; and a magnet coil 216e is associated with the strip 220e.

A magnet 344, similar to the magnets 110, is associated with 216 and 216a and is provided with members (not shown) associated with the armature thereof for exerting additional pressure on the armatures carrying the contact strips 220 and 220a. A similar magnet 345 is associated with the magnet coils 216b and 216c and a magnet 346 is associated with 216d and 216e, all being arranged to exert extra pressure on the contacts controlled by the magnet coils 216a and 216c inclusive.

Connections to these magnets may be traced as follows:

From the bus wire 322 via a wire 347 to one terminal of the magnet 216e, from the other terminal of 216e via a wire 348 to one terminal of the magnet 346, from the other terminal of the magnet 346 via the wire 349 to one terminal of the coil 216d. The other terminal of the coil 216d is connected via the wire 350 to the contact 351 of the triple pole, double throw switch 352. The wire 350 is also connected to the contact 353 of a triple pole, double throw switch 354, and to the contact 355 of a triple pole, double throw switch 356.

The wire 347 branches and is connected to one terminal of the coil 216c and to one terminal of the coil 216a. The magnets 216c, 345 and 216b are connected in series by means of wires 357 and 358, and a wire 359 connects the magnet 216b to the contact 360 of the switch 352, to the contact 361 of the switch 354 and to the contact 362 of the switch 356.

The magnets 216a, 344 and 216 are connected in series by means of wires 363 and 364. The magnet 216 is connected by a wire 365 to the contact 366 of the switch 352, to the contact 367 of the

switch 354 and to the contact 368 of the switch 356.

The contacts 263b associated with the "hundreds" keys in the row 369, and also the 0 contact 280b, are connected via a cable 370 as follows:

The 0 contact 274b is connected to the contact 371 of the switch 352, the 1 contact is connected to the contact point 372, the 2 contact is connected to the contact point 373 of the switch 352. The 3, 4 and 5 contacts are connected respectively to the contact points 374, 375 and 376 of the switch 354. The 6, 7 and 8 contacts are connected respectively to the contact points 377, 378 and 379 of the switch 356.

The contact 263b, associated with the 9 key 15 in the "hundreds" row is connected to the contact points 380, 381 and 382 of the switch 352. The switch 352 is provided with blades 383, 384 and 385. The switch 354 is provided with blades 386, 387 and 388, and the switch 356 is provided 20 with blades 389, 390 and 391.

The relay 175a has one terminal of its coil 176a connected via a wire 392 to the helical wire 121a. The other terminal of the coil 176a is connected via a wire 393 to a resistor 394 which in turn is 25 connected to the bus wire 322. The wire 393 branches and is also connected to one terminal of each of the magnets 176g and 176h. The other connections to the magnets 176g and 176h will be presently described in connection with the "sub-total" counter and the "miscellaneous" counter, which are of the type shown in Figure 10.

The relay magnet 176b has one terminal connected via a wire 395 to the helical wire 120. The other terminal of the magnet 176b is connected 35 via a wire 396 to a limiting resistor 397 which is in turn connected to the bus wire 322.

The helical wires 121 and 120a are connected in common and are connected via a wire 398 to a contact 399 associated with the sub-total key 400 and to a contact 401 associated with the motor bar 402, and a wire 403 connected to the wire 398 is in turn connected to a condenser 404 and a leaking resistor 405. A wire 406 connected in common with the other side of the condenser 404 and the resistor 405 is in turn connected to the total-bills counter magnet 168 and to a contact arm 407 associated with the motor bar 402.

A wire 408 is connected to the wire 403 and connects to the contact arm 274f which forms a part of the "zero" circuit of the machine. The remainder of the "zero" circuit will presently be described.

One terminal of the adding machine motor 409 is connected by means of a wire 410 to a contact arm 411 associated with the grand total key 412 and is also connected to the contact arms 180a, 180h and 180g associated with the magnets 176a, 176h and 176g respectively. The contact arm 183a is connected via a wire 413 to the contact arm 180b. The contact arms 183b, 183h and 183g are connected together by means of a wire 414 which is in turn connected to a contact arm 415 associated with the grand total key 412.

The other terminal of the motor 409 is connected via a wire 416 which is in turn connected to a wire 417 leading to the negative side of the source of current.

The wire 417 is also connected to a contact point 418 of the switch 333. A plate 419 is provided for connecting the contact point 418 to the contact point 420. The wire 421 connects the contact point 420 to a contact point 422 of the switch 327.

A plate 423 is provided for connecting the contact point 422 to a contact point 424. A wire 425 connects the contact point 424 to the wire 398 above described which connects the helical wires 121 and 120a together and to the sub-total key and the motor bar. The other terminal of the magnet 176h is connected by means of a wire 426 to one side of the sub-total counter magnet 168h and to the contact arm 435 associated with the sub-total key 400.

The other terminal of the magnet 176g is connected by means of a wire 427 to one side of a miscellaneous counter magnet 168g. The wire 427 branches and connects via a wire 428 to contact points 283c, 283d, 283e and 283f, and to contact points 429, 430 and 431 associated with the switch 354, and 432, 433 and 434 associated with the switch 356.

The other sides of the "total bills" counter magnet 168, the "sub-total" counter magnet 168h, and the "miscellaneous" counter magnet 168g are connected by means of a wire 436 to a limiting resistor 437. The other side of the limiting resistor is connected to the bus wire 322.

The return wire of the 0 magnet 112 in the bank 307 is connected via a wire 438 to a contact arm 283g. A wire 439 connects the contact arm 283g to the contact arm 280r. The contact arm 274r is connected via a wire 440 to the contact arm 283a.

As pointed out above, the contact arms 264 associated with the keys in the "units" row 303 are connected in common by a wire 308 and the contact arms 264a associated with the "tens" keys 309 are connected in common by a wire 314.

The contact arms 264b which are associated with the "hundreds" row 369 are connected in common by means of a wire 441. The wires 308, 314 and 441 are connected together by means of a wire 442 which is connected to the contact arms 274, 274a and 274b. A branch wire 443 is connected to the wire 442 and to the contact arm 280c and 280g. The contact arm 274c is connected to the contact arm 280d, the contact arm 274d is connected to the contact arm 280e; and the contact arm 274e is connected to the contact arm 280f.

A branch wire 444 connects to the motor lead 410 and to the contact arm 248. The contact arm 249 is connected via a wire 445 to the wire 336. The statistical mechanism is disconnected from the adding machine by depressing the "off" key 230. The contact points 246 and 247 are opened and the contact points 248 and 249 are closed. This last pair of contact points permit the current to flow to the motor so that the adding machine can be operated by means of its motor bar 402 in the usual manner, when a statistical count is not desired.

Where alternating current mains only are available to supply current to the machine, a suitable rectifier (not shown) may be provided for changing the alternating current into direct current, in which case the negative lead from the rectifier would be connected to the contact point 447 of switch 333 and also to the contact point 448 of the switch 327. The positive lead from the rectifier would be connected to the contact point 449 of the switch 333 and also to the contact point 450 of the switch 327.

In this case, the switch blades would be thrown so that the blade 334 connects the switch contact 335 to the contact 449. The blade 419 would connect the contact 418 to the contact 447 in the switch 333. In the switch 327, the blade

328 would connect 328 to the contact 450 and the blade 423 would connect 424 to the contact 448.

The last row of keys to the left (the hundred thousand row), in the adding machine, designated by the numeral 446, might be termed the "zero-zero" keys, and when any key in this row is actuated the contact points 280g and 283g are closed.

Whenever a customer's bill shows the non-use of current (during the conducting of a rate study) it is required to record "No bill", in which case the 0 or "zero-zero" counter should be actuated. This is accomplished as follows:

When any of the keys in the row 446 is depressed, as pointed out above, the contacts 280g and 283g are closed, thereby establishing a circuit which may be traced as follows:

The wire 438, which extends from one terminal of the 0 magnet in the bank 307 to the contact arm 283g, is connected via the contact arm 280g to the wire 443, which is in turn connected to one side of the 0 magnets in all of the other banks of magnets via the contact arms 274a, 280a, and the cable 310, and via the contact arms 274, 280 and the cable 304.

The wire 443 is also connected via the contact arms 274b, 280b and the cable 370 to the "zero" contact 371 in the switch 352. The blade 385 connects the switch contact 371 to the contact 360. The wire 359 from the contact 360 is connected to one terminal of the magnet 216b. The circuit from the other terminal of 216b leads via the wire 358, the magnet 345 and thence via the wire 357 to one terminal of the magnet 216c, from the other terminal of the magnet 216c, a wire 347 connects to the bus wire 323, to the platen contacts 294, 295 and via the wire 324 to the yield contacts 258, 259, thence via the wire 325 to the "on" contacts 246, 247, thence via the wire 326 to the center contact 328 of the switch 327, and via the switch blade 329 to the contact 330. Leaving the contact 330 the circuit extends via the wire 331 to the contact 332 of the switch 333, via the blade 334 to the contact 335, and via the wire 336 to the positive terminal of the source of current.

After depressing the "zero-zero" key, as above described, the motor bar 402 is depressed, thereby closing the contacts 401, 407, after which the circuit extends from the wire 443 via the contacts 280c, 274c, 280d, 274d, 280e, 274e, 280f, 274f, and via the wire 408 to the contact 407, thence to the contact 401 and via the wire 398 to the helical wires 120a and 121.

A wire 425, connected to the wire 398 leads through the switch 327 via the contact 424, the blade 423, the contact 422 and from 422 via the wire 421 to the contact 420, the blade 419 and the contact 418 of the switch 333, and thence via the wire 417 to the negative side of the source of current.

As the act of depressing the motor bar, after the depression of one or more of the adding machine keys, completes the circuit as above traced from one polarity of a source of current to the other, the magnets 216b, 345 and 216c are energized, thereby connecting the contacts 225c to the strip 220c and the contacts 225b to the contact strip 220b. The connection of the plunger contacts 225c to the strip 220c energizes any magnet in the bank 307 which has had its return circuit completed. As above described, the return circuit of the 0 magnet in this bank was completed by 75

the depression of a "zero-zero" key. This circuit may be traced as follows:

From the bus wire 322 above described, via the limiting resistor 321 and the wire 320 to the contact strip 220e, thence via the contact arm 222e and the wire 319 to the contact strip 220a, and to the contact arm 222a. From the contact arm 222a the circuit leads through the wire 343 to the contact strip 220c. Since the contact strip 220c is in contact with the ten plunger contacts 225c, one side of all the magnets in the bank 307 is connected to the bus wire 322.

The 0 magnet in the bank 313, as well as the 0 magnets in all of the other banks, has one terminal thereof connected to the wire 443 as above described.

Due to the contact established between the strip 220b and the plunger contacts 225b, when the magnet 176b was energized, connection to the other side of the magnet coils in the bank 313 may be traced as follows:

From the bus wire 322 via the limiting resistor 339 and the wire 338 to the contact strip 220d and via the contact arm 222d and the wire 316 to the contact strip 220, thence via the contact arm 222 and the wire 317 to the contact strip 220b, thence via the plunger contacts 225b and via the cable 341 to one side of all the magnets in the bank 313. Since the 0 magnet is the only one in this group to have its return circuit completed, it is the only one in this group which will be actuated. As a result of the depression of the motor bar the 0 magnet in the bank 307 and the 0 magnet in the bank 313 are actuated with the result that the 0 counter is selected for actuation.

The 0 magnet in the bank 313 may be considered to correspond to the magnet 110 shown in Figure 13 and the 0 magnet in the bank 307 corresponds to the magnet 112. The arm 111 associated with the armature 115 acting against the domed end of the cup 104, associated with an engaging member 106 carried by the shaft 66e, for example, and the arm 124 associated with the magnet 112 will act against the domed end of the engaging member carried on the shaft 65e, the shafts 65e and 66e being assumed to be associated with the 0 counter.

At the same time, the helical wires 120 and 121 are moved into engagement with the metallic strip 123 and the helical wires 120a and 121a are moved into contact with their associated metallic strip 123. The relays 176a and 176b are energized due to the establishment of contact between the helical wires 120a, 121a and/or 120, 121, respectively. The circuit through 176a may be traced as follows:

From the bus wire 322 via the limiting resistor 394 and via the wire 393 to one terminal of the magnet 176a. From the other terminal the circuit may be traced via the wire 392 to the helical wire 121a thence via the contact strip 123a to the helical wire 120a and via the wires 398, 425 through one side of the switch 327 and via the wire 421 to one side of the switch 333 and via the contacts and blades in one side of this switch and the wire 417 to the negative side of the source of current, therethrough the relay 176a is energized. The circuit through the contacts of this relay will presently be described in connection with the adding machine motor circuit.

The relay 176b is energized as follows:

Current flows from the bus wire 322 via the limiting resistor 397 and the wire 396 to one terminal of the magnet 176b and out from its

other terminal via the wire 395 to the helical wire 120 and thence via the contact strip 123 to the helical wire 121 and via the wire 398, one side of the switches 327 and 333 and via the wire 417 to the negative side of the line, thereby energizing the relay 176b and closing its contacts 180b and 183b.

As above described, when the relay 176a was actuated, its contacts 180a and 183a were closed. The closing of both of the contacts of both of these relays established a circuit to the motor 409 of the adding machine which may be traced as follows:

From the positive side of the line, via the wires 336, 445, 451 and 414 to the contact arm 183b, thence to the contact arm 180b and via a wire 413 to the contact 183a. From the contact arm 183a current flows to the contact arm 180a and via the wire 410 to one side of the motor 409. From the other side of the motor current flows via the wire 416, the wire 417 and to the negative side of the source of current. Therefore, as soon as the 0 magnet in the bank 307 is actuated, closing the circuit to the relay 176b, the motor 409 operates, thereby actuating the adding machine and motion is transmitted via 93, Figure 14, to the shaft 94 and via the gears 96 and 98 to the shaft 95, Figure 11, and via the yield member to the lever 79 and thence via the link 76 to the bar 71.

Since the engaging member associated with the shaft 65e of the 0 counter and the engaging member associated with the shaft 66e of the 0 counter, have been actuated by the magnets 110 and 112, as above described, and are in engagement with pins 109, the movement of the bar 71 will actuate the 0 counter and cause the same to add a 1. This action has been previously described in connection with the description of Figures 5, 6, 7, 8, 9 and 11.

One of the counters, of the type shown in Figure 10, is provided to count the total number of bills handled during a rate study and accordingly it also will be actuated due to this operation. The magnet controlling this counter is designated by the numeral 168 and its circuit may be traced as follows:

From the bus wire 322 via the limiting resistor 437 and the wire 436 to one terminal thereof and from the other terminal via the wire 406 to the contact arm 407 of the motor bar, and thence to the negative side of the line, as above described.

Assuming that the next customer's bill is for \$1.95, the 1 key would be depressed in the row 369, the 9 key in the row 309 and the 5 key in the row 303.

Taking the row 303 first for purposes of description, the contacts 263 and 264 associated with the 5 key would be closed and the release of the differential stop bar and mechanism associated therewith would open the 0 circuit above described, thereby connecting one side of the 5 magnets in the bank 305, 306 and 307 to the motor bar contact arm 407, the connection being via the cable 304, contacts 263 and 264 associated with the 5 key (in the row 303) via the wires 308, 442 and 443, the contacts 280c, 274c, 280d, 274d, 280e, 274e, 280f, 274f and thence via the wire 408 to the contact arm 407.

The depression of the 9 key, in the row 309 closes the contacts 263a and 264a associated with this key and the portion of the 0 circuit associated with the differential stop bar of this row, causes the contact arm 274a to break contact with 280a and to establish contact with 283a, thereby

disabling the "tens" portion of the "zero" circuit. Due to the closing of the contacts 283a and 284a associated with the 9 key, one side of each of the 9 magnets in the banks 311, 312 and 313 to the motor bar contact arm 407.

When the 1 key in the row 368 is depressed, the 0 contacts 280b and 274b are opened and the contact arms 263b and 264b associated with the 1 key are closed, thereby, via the cable 370, connecting the center contact 372 of the switch 352 to the motor bar contact 407.

The contact 372 is also connected by the switch blade 384 to the contact 351 which is in turn connected via the wire 350 to one terminal of the magnet 216d. From the other terminal of the magnet 216d a wire 349 leads to the magnet 346 and thence via the wire 348 to one terminal of the magnet 216e. The other terminal 216e is connected via the wire 347 to the bus wire 322.

Current flowing through the magnets 216d, 346 and 216e causes the metallic strip 220e to contact the plunger contacts 225e and also cause the contact strip 220d to contact the plungers 225d. When this occurs, current will flow from the bus wire 322 via the limiting resistor 321 and a wire 320 to the contact strip 220e. Since the plungers 225e are connected via the cable 340 to one side of each of the magnets 306, and since the 5 magnet in this bank is the only magnet to have had its return circuit completed, this magnet will become energized.

Current flows from the bus wire 322 via the limiting resistor 339 and the wire 338 to the contact strip 220d and via the plunger contacts 225d, with which the strip is in contact, through the cable 337 to one side of each of the magnets in the bank 312.

Since the 9 magnet is the only magnet in this group which was energized when the 9 key in the row 309 is depressed, this magnet in the bank, only, will be energized.

The 9 magnet in the bank 312 actuates an engaging member associated with one of the shafts 66, and the 5 magnet in the bank 306 actuates an engaging member carried on a shaft 65e, these engaging members being associated with the 9 magnet and 5 magnet aforesaid, respectively, and the operation of these two specific engaging members associates a 95 counter in a group of counters designated as "hundreds" counters (containing counters from 100 to 199).

The actuation of the 1 key in the "hundreds" column 369 actuates the relays 216d, 246 and 216e and causes the selection of the counters in the "one hundred" group above mentioned.

If the 2 key in the "hundreds" column had been depressed, instead of the 1, the contact 373 of the switch 352 will have been connected instead of the contact 372, in which case the relays 216, 344 and 216a would have been selected, due to the fact that the wire 365 fitting the relay 216, is connected to the contact 366 and the switch blade 383 connects 373 to 366.

If the amount had been \$.95, instead of \$1.95, the 0 contact arms 280b and 274b would not have been opened and the contact 271 would have been connected to the wire 443, thereby selecting the relays 216b, 345 and 216c through the medium of the wire 359 as above described in connection with the recording of a "no bill".

It must be borne in mind that counters recording amounts from 0 to 99 are selectively associated with the mechanism by means of any combination of magnets in the banks 307 and 313, the selection of which magnets is in turn controlled

by the relays 216b, 345 and 216c. Counters recording amounts from 100 to 199 are selectively associated with the mechanism by means of any combination of magnets in the banks 306 and 312, the selection of which magnets is in turn controlled by the relays 216d, 346 and 216e. Counters recording amounts from 200 to 299 are selectively associated with the mechanism by means of any combination of magnets in the banks 305 and 311, the selection of which magnets is in turn controlled by the relays 216, 344 and 216a.

When the switches 352, 354 and 356 are connected, as shown in the circuit diagram, by throwing the blades of the switch 352 to the left, as viewed in the diagram, and by throwing the blades of the switch 354 to the right, as shown in the diagram, the 0 to 99 counters may be made to record bills in amounts from 300 to 399. The 100 to 199 counters may be made to record bills in amounts from 400 to 499; and the 200 to 299 counters may be made to record bills in amounts from 500 to 599.

If it is desired to go higher, the blades of the switch 352 may be allowed to remain thrown to the left, as just described; the blades of the switch 354 may be thrown to the right, in which case the 0 to 99 counters may be made to record bills in amounts from 600 to 699, the 100 to 199 counters may be made to record bills in amounts from 700 to 799, and the 200 to 299 counters may be made to record bills in amounts from 800 to 899, etc.

In making a rate study, in the range from 0 to 299, in case some larger bills appear in the group, they are automatically thrown into the miscellaneous counter which is controlled by the magnet 168g. In that case, the switches 352, 354 and 356 are positioned as shown in the diagram, in which the contacts associated with the 300 to 899 keys inclusive are connected by the cable 370 to the center contact of the switches 354 and 356 and via the blades of these switches to the contacts designated as "miscellaneous", which are all connected together, and are in turn connected via the wire 428 to the magnet 168g controlling the miscellaneous counter.

It must be borne in mind that each bank of counters contains a group of 100 counters. Ten upper magnets 110 and ten lower magnets 112 control the selection of any one of the hundred counters in a bank of actuation. For example, a 0 magnet in the upper row and a 1 magnet in the lower row will effect the selection of a 1 counter. On the other hand, a 1 magnet in the upper row and a 0 magnet in the lower row will select a 10 counter. An 8 magnet in the upper row and a 9 magnet in the lower row will select an 89 counter, whereas a 9 magnet in the upper row and an 8 in the lower row will select a 98 counter.

It is obvious that the adding mechanism can be omitted, and a driving mechanism substituted therefor, in which case the keys would control the selective association of the counters with said mechanism; in cases where totalizing the amounts of the bills is not desired, or where they are totalized otherwise.

Although a simple embodiment of the invention is herein shown and described, it is obvious that many changes can be made by those skilled in the art without departing from the spirit of the invention as defined in the following claims.

What is claimed is:

1. A statistical machine comprising a mecha- 75

- nism having an extended shaft, a row of "units" keys, a row of "tens" keys, and a row of "hundreds" keys for setting up indications; a pair of contacts and a plurality of magnetically operated devices interconnected therewith associated with each key in said "units" and "tens" rows, a pair of contacts and a relay interconnected therewith associated with each key in said "hundreds" row for controlling said magnetically operated devices, a plurality of banks of counters, a counter actuating mechanism operatively connected to said shaft, and actuating members for said counters conjointly controlled by a "units" key, a "tens" key and a "hundreds" key for selecting one of said banks and for placing a single counter in the bank selected in operative relation with said actuating mechanism.
2. A statistical machine comprising a mechanism, a plurality of rows of keys, a plurality of banks of counters, a pair of contacts and a plurality of magnets, each having one terminal thereof interconnected therewith associated with each key in one of said rows, a pair of contacts and a plurality of magnets interconnected therewith associated with each key in the second of said rows, a pair of contacts associated with each key in a third of said rows, a plurality of relays, switching means for associating said relays with the contacts of some of the keys in said third row, each relay being adapted to control the completion of circuits to the other terminals of the magnets in one of said banks thereby assigning a certain value to said banks, other circuits associated with said switching means whereby said relays may be associated with other keys in said third row thereby in effect assigning different values to said banks, and engaging members conjointly controlled by a magnetic device associated with one of the keys in the first row and by a magnetic device associated with one of the keys in the second row for placing one of said counters in operative relation with said mechanism.
3. A statistical machine including a mechanism having an extended shaft, a row of "units" keys, a row of "tens" keys and a row of "hundreds" keys for effecting setups therein; a plurality of banks of counters, each bank representing different "hundreds" values and the individual counters in each bank representing the "units" and "tens" values of said "hundreds"; counter actuating mechanism moved by said shaft; a plurality of engaging members operatively connected to said counters and adapted to be magnetically shifted into engagement with said actuating mechanism; a magnet for each engaging member, said magnets being arranged in two groups whereby the combination of one magnet in each group shifts corresponding engaging members into engagement with said actuating mechanism, thereby causing the counter corresponding to the combination to operate and add one, each magnet having an actuating circuit terminal and a return circuit terminal; a pair of contacts associated with each of said keys; connections between the contacts associated with said "units" and "tens" keys and the actuating circuit terminals of said magnets; a plurality of relays; connections including the contacts of said "hundreds" keys, said relays and the return circuit terminals of said magnets; and zero circuits including separate switching means associated with each of said rows of keys and including magnets associated with 0 counters in said banks, said zero circuits being normally effective when no key in either of said rows is depressed and

adapted to have a portion disabled when a key in the row with which said portion is associated is depressed.

4. In a statistical machine, a plurality of rows of keys for setting up identifications, a pair of contacts for each key, a plurality of counters, motor driven mechanism including an oscillatable shaft, counter actuating mechanism operatively connected to said shaft, including engaging members and link control members conjointly adapted to place a counter in driven relation with said actuating mechanism, each of said pairs of contacts associated with the keys in one of said rows having a circuit interconnected therewith and including a magnet for actuating one of said engaging members, each of said pairs of contacts associated with the keys in another of said rows having a circuit interconnected therewith and including a magnet for actuating one of said link control members, a circuit for said motor, and contact devices controlled by said magnets for completing said motor circuit after a counter is selected and placed in driven relation with the actuating mechanism.

5. A statistical machine comprising a plurality of rows of keys for setting up indications, mechanism including an oscillating shaft, a motor for driving said mechanism, a plurality of counters, one for each key and combination of said keys, actuating mechanism including a driving member associated with said shaft, counter-engaging mechanism interposed between said actuating mechanism and said counters, means for controlling the operation of said counter-engaging mechanism comprising a pair of contacts and a plurality of magnetically operated devices associated with some of said keys, and contacts and relays associated with others of said keys whereby the conjoint operation of two of said keys having associated magnetic devices and one of said keys having contacts and a relay as aforesaid will effect said control of said counter-engaging mechanism, a circuit for said motor, and means associated with said counter-engaging mechanism for enabling said motor circuit only after a selected counter has been engaged.

6. In a statistical machine, a plurality of denominational rows of keys, a pair of electrical contacts for each key, a plurality of counters each representing a setup in said keys regardless of whether said setup involves a single key in either of said rows or combinations of said keys, mechanism including an oscillatable shaft, a motor operatively connected to said mechanism, counter actuating means operatively connected to said shaft, an engaging member for each counter, a link for each counter, each link being adapted to place its counter in driven relation with said actuating mechanism, a magnet for each key included in a circuit with the pair of contacts associated with its key, said magnets being adapted to actuate said engaging members, other magnets included in circuits with the contacts of the keys in another of said rows for controlling the positioning of said links, a bar for each of said rows of keys, each bar being adapted to move when a key in the row in which it is associated is depressed, "zero" contacts normally closed and adapted to be opened by the movement of said bars, "zero" circuits including said "zero" contacts and magnets for controlling those of said counters which represent "zeros" of different denominations, whereby said "zero" counters are automatically selected when no key in the row

representative of "tens" or "hundreds" is depressed.

7. In a key-set device of the character described, mechanism including a rocking shaft, means for driving said mechanism, a bar reciprocated by the movement of the shaft, a counting device including counter wheels and pawls for actuating the same, a lever for moving said pawls, a stud secured to said lever, a second bar having a longitudinal slot formed therein and adapted to ride said stud when reciprocated lengthwise, a strip having a transverse slot formed therein engaging said stud normally with its slot substantially parallel to said first slot, a shaft carrying an arm adapted when oscillated to move said strip, a second shaft linked to said second bar and adapted when rotated a portion of a revolution, to position the second bar with its slot in angular relation to the slot in said strip, a pair of studs carried by said first bar, engaging members shiftably carried by each of said shafts and adapted to engage said studs, a pair of contacts in circuit with a magnetic device operated by one of said keys to cause one of said engaging members to shift into engagement with one of said studs for positioning the slot in said second bar as aforesaid, and a pair of contacts in circuit with a magnetic device operated by another of said keys to cause the other of said engaging members to engage said other stud to effect the movement of said strip, thereby causing the motion of said first bar to be imparted to said pawls via said lever.

8. A statistical machine comprising a mechanism having an operative shaft and including a plurality of keys arranged in denominational rows as on an adding machine, a plurality of counters adapted to be actuated by the movement of said mechanism through the medium of said shaft, a plurality of magnets for selectively associating any one of said counters with said shaft, electrical contacts controlled by said keys, electrical circuits including said magnets and said contacts, said magnets acting in combinations of two for selectively associating a counter and said shaft, a motor for driving said mechanism, a source of current, a circuit for said motor adapted to be enabled when a counter is associated with said shaft, and a motor bar having contacts included in said motor circuit, whereby said motor may be energized after a counter is selected and associated with said shaft.

9. The invention according to claim 8 in which said mechanism is driven by an electric motor, in which a motor bar key is provided, and in which said magnets also control contacts which are included in circuits with the motor, a source of current and said motor bar.

10. A statistical machine comprising a plurality of keys arranged in denominational rows as in an adding machine, mechanism including an oscillative shaft, a motor operatively connected to said mechanism, a movable bar associated with each of said rows of keys, zero circuits controlled by each of said bars and adapted to be disabled when a key in the row with which a bar is associated is depressed, a pair of contacts and a plurality of magnets in circuit therewith associated with each key in at least two of said rows, a pair of contacts and a relay interconnected therewith and associated with some of the keys in another of said rows for controlling the energization of said magnets, a plurality of banks of counters, the counters in one of said banks normally representing numerical values of less than three fig-

ures, contacts and circuits associated with said bars each being adapted to be disabled when one of its associated keys is depressed; the contacts controlled by the bar associated with said last row of keys being normally connected to control the energization of the magnets associated with said counters representing numerical combinations of less than three figures, whereby a magnet controlled by any one of said first rows and a magnet controlled by the other of said first rows conjointly associate a counter with said mechanism in accordance with the positions of the contacts controlled by keys in said first rows and the bar in said another row.

11. A statistical machine comprising a plurality of rows of keys, mechanism including a movable shaft, a plurality of banks of counters, a reciprocable mechanism operatively connected to said shaft, a motor for driving said mechanism, magnetically controlled engaging means between each counter and said reciprocable mechanism, a plurality of magnets constituting the controls for said engaging means for selectively associating any one of said counters with said reciprocable mechanism, electrical circuits including said magnets and those of said contacts associated with two of said rows of keys, said magnets acting in combinations of two for selectively associating a counter with said reciprocable mechanism, relay means connected in circuits with the contacts associated with another of said rows of keys for determining in which of said banks the counter selected falls, a "zero" circuit associated with said last row of keys to cause the counter selected to fall in the first of said banks of counters representing values of less than one hundred if no key is depressed in said last row, a circuit for said motor and contacts controlled by said magnets for enabling said motor circuit after a counter has been selected.

12. In a statistical machine, in combination, a mechanism, a plurality of rows of keys, a shaft included in said mechanism which oscillates during each operating cycle of said mechanism; a plurality of counters; counter actuating mechanism driven by said shaft, a plurality of forked members associated with said counters, each adapted to be magnetically moved into engagement with said actuating mechanism; a magnet for each of said members; a pair of contacts associated with each of said keys; a plurality of circuits including said contacts and said magnets; a bar associated with each row of keys, each bar controlling contacts normally maintaining a "zero" circuit until a key in the row in which it is associated is actuated, thereby disabling its "zero" circuit and establishing one of said first circuits, relays included in circuits with the contacts in another row of said keys for determining which bank the selected counter will fall in, whereby each of said keys and each combination of said keys will effect the selection of a different counter, a motor for driving said mechanism, a motor bar, a circuit for said motor including contacts controlled by said motor bar and adapted to be enabled when said motor bar is depressed, and connections from said last circuit to a source of current.

13. In a statistical machine, mechanism including a rocking shaft, a motor in driving relation to said mechanism, a plurality of rows of keys, a bar reciprocated by the movement of said shaft, a counting device including counter wheels and pawls for actuating the same, a lever for moving said pawls, a stud secured to said lever, a second bar having a longitudinal slot

- formed therein and adapted to ride said stud when reciprocated lengthwise, a strip having a transverse slot formed therein engaging said stud normally with both of said slots substantially 5 parallel, a shaft carrying an arm adapted when oscillated to move said strip, a second shaft linked to said second bar and adapted when rotated a portion of a revolution, to position the second bar with its slot in angular relation to the slot in 10 said strip, a pair of studs carried by said first bar, engaging members shiftably carried by each of said shafts and adapted to engage said studs, a pair of contacts in circuit with a magnetic device operated by one of said keys to shift one of 15 said engaging members into engagement with one of said studs for positioning the slot in said second bar as aforesaid, and a pair of contacts in circuit with a magnetic device operated by another of said keys to cause the other of said 20 engaging members to engage said other stud to effect the movement of said strip, thereby causing the motion of said first bar to be imparted to said pawls via said lever.
14. In a key-set statistical device, mechanism including a driving shaft, a plurality of counting devices, actuating mechanism for said counters including a driving member driven by said shaft, counter engaging mechanism interposed between said actuating mechanism and said counters, a 25 pair of electrical contacts associated with each key, means for controlling the operation of said counter engaging mechanism comprising electrical circuits including said contacts and magnetically operated devices for shifting said counter engaging mechanism into engagement with said actuating mechanism whereby a counting device the identity of which is represented by the key or combination of keys operated is placed in driven relation with said actuating mechanism 30 and caused to count "one" when said driving shaft is operated, a motor for driving said first mechanism, a circuit for said motor, a motor bar, contacts controlled by said motor bar and included in the circuit of said motor, and connections from said circuit for said motor to a 35 source of current.
15. In a device of the character described, a plurality of rows of keys, a mechanism and means for driving the same; an oscillatable shaft, a reciprocable bar operatively associated with said shaft, a counting device including counter wheels and pawls for actuating the same, a lever for moving said pawls, a stud secured to said lever, a second bar having a longitudinal slot formed 40 therein and adapted to ride said stud when reciprocated lengthwise, a metallic strip having a 45 transverse slot formed therein engaging said stud normally with its slot substantially parallel to said first slot, a shaft carrying an arm adapted when oscillated to reciprocate said strip, a second shaft linked to said second bar and adapted, when rotated a portion of a revolution, to position the strip with its slot in angular relation to the slot in said second bar, a pair of studs carried by said first bar, engaging members shiftably carried by each of said shafts and each adapted to engage 50 one of said studs, magnetic means and a circuit therefor including contacts associated with one of said keys for shifting one of said engaging members to effect the positioning of the slot in said strip and magnetic means and a circuit therefor including contacts associated with another of said keys for shifting the other of said engaging members to effect the reciprocation of said strip and the actuation of said counter.
16. In a device of the character described, a plurality of rows of keys, mechanism including a moving shaft, a plurality of counters, an oscillating bar driven by said shaft, counter actuating means conjointly controlled by a combination of said keys for associating one of said 55 counters in driven relation with said bar, a pair of contacts associated with each key and a plurality of circuits including said contacts and said means, a source of current for supplying current to said circuits, balanced resilient means connected between said shaft and the counters to prevent damage to either when said means fails to operate in a normal manner, electrical circuits associated with said means, and a pair of contacts in series with said circuits and said 60 source and adapted to disable said circuits when said resilient means is unbalanced.
17. The invention according to claim 16 in which a motor is provided for driving said mechanism; and in which said pair of contacts, in 65 series with said circuits and said source, in addition to disabling the other circuits in the device, also deprive the motor of current, thereby preventing said counter from becoming wrecked.
18. A statistical machine according to claim 8, 70 in which each of said denominational rows of keys has associated therewith a movable bar, a zero circuit for each of said movable bars and a pair of contacts in each of said zero circuits adapted to be disabled by its movable bar when 75 a key in the denominational row with which the bar is associated is depressed, thereby eliminating the necessity for including zero keys in said denominational rows.

WILLIAM B. AUSTIN.
